SYSTEM FOR AMPLIFICATION

Lewis M. Hull, Boonton, N. J., assignor, by mesne assignments, to Radio Corporation of America, New York, N. Y., a corporation of Delaware

Application June 14, 1926. Serial No. 115,929

4 Claims. (Cl. 250—20)

This invention relates to an amplifying system of the type adapted to employ audion tubes. It provides a system suitable for use in amplifying audible frequencies, and may be used in the arts of wire telegraphy or telephony, or in any situation where amplification of sound is desired. It is useful also in the arts of wireless telegraphy or telephony; and may be appropriately applied either to a transmitting system in which it is desired to amplify before transmission, or to a receiving system in which it is desired to amplify received signals. It provides a system for producing any desired number of separate amplifications of a modulated carrier oscillation while retaining the characteristic modulation thereof. It also provides a system whereby audio frequencies, either singly or in a complex group, may be subjected to amplification at super-audible frequencies. It may also provide a system in which one audio frequency, or a plurality of audio frequencies composing a complex group of frequencies, originally transmitted on a particular carrier frequency are amplified at a different frequency, which may be any super-audible frequency, as, for example, an intermediate frequency; or are successively amplified at a plurality of the same or different super-audible frequencies, as desired. I have found it to be particularly suitable for use in a radio receiving set employing intermediate frequency amplification.

In audion amplifier apparatus it has long been the custom to amplify the oscillations either at so-called radio frequencies or at audio or audible frequencies. While it is impossible to define the limits of these ranges it may roughly be said that the audible range is from approximately 50 to 30,000 cycles per second, while the radio frequency range is generally thought of as being considerably higher. In present day commercial "broadcasting" the frequencies of the carrier waves may vary from about 500 to 1500 kilocycles. In ordinary amplifying apparatus it is common to employ one or more stages of radio frequency amplification adapted to amplify at the frequency of the incoming carrier wave, pass the amplified oscillations through a detector in order to convert them to audio frequency, and again amplify at audio frequency.

While this method is often satisfactory, there are certain structural and operational difficulties in cascading a large number of either radio frequency or audio frequency stages. Among these may be mentioned the stray capacities and parasitic losses which inevitably occur in a high-fre-

quency amplifier, especially if it is of the short-wave type, unless it is carefully compensated and shielded; and the distortion which often results when more than two stages of audio frequency amplification are cascaded. To avoid these and other difficulties it has heretofore been proposed to perform a part of the amplification at so-called intermediate frequencies. By intermediate frequencies is meant frequencies which are lower than those ordinarily considered as radio frequencies, but which are yet so high as to be without the audible range. It is now a well recognized fact that certain advantages may arise from such intermediate frequency amplification.

One method of intermediate frequency amplification, which however is applicable only to systems receiving radio frequencies and not to the amplification of audio frequencies, is that which is now commercially known as the super-heterodyne. In the operation of this system an incoming modulated radio frequency wave is made to beat with oscillations produced by a local oscillator or heterodyne. The beat frequency equal to the difference between the incoming frequency and the heterodyne frequency is detected and amplified by a fixed intermediate frequency amplifier which is usually designed to be sharply responsive to this particular frequency. The receiver is dependent for its selectivity upon the resonance characteristics of the amplifier. The frequency reduction is brought about by a beat method, and since the intermediate frequency amplifier is fixed and sharply responsive, it is necessary, in order to receive radio frequency signals of various frequencies, simultaneously to change the setting of both the radio frequency receiver and the oscillator in such a manner that the difference between their frequencies may be constantly equal to the desired intermediate frequency.

The super-heterodyne method of receiving is open to a number of objections. Among the more serious difficulties is that just indicated as arising from the necessity for simultaneously varying the tuning of the high frequency amplifier and of the local oscillator, when incoming signals of different frequencies are to be received. The oscillator requires a separate control which cannot readily be combined with the tuning controls of the high frequency amplifier. Moreover, it is difficult to maintain a constant frequency in the oscillator and so avoid variations in the beat frequency. A serious objection is that due to the necessity for a sharply resonant intermediate frequency amplifier, which prevents the

105

110

use of certain desirable non-selective amplifiers, such as those having resistance coupling. Another objection arises from the fact that there are two frequency settings of the local oscillator 5 which produce a response to the same incoming signal. Such a response occurs when the frequency of the oscillator is either greater or less than that of the incoming carrier wave by an amount equal to the frequency to which the intermediate frequency amplifier is responsive. Still another objection is that during the process 10 of tuning, the oscillator may produce audible beats with the incoming carrier wave. These beats are relayed by the subsequent amplifiers, 15 and may cause a disagreeable sound or "squeal".

To avoid these and other difficulties, I have invented a system for amplifying audio frequency currents at higher or super-audible frequencies. This amplifying system may either be 20 applied directly to the amplification of audio frequency currents, or may be incorporated in a radio receiver.

In Fig. 1 I have diagrammatically represented a simple form of my invention. A source of 25 audio frequency current which it is desired to amplify is shown at I. This frequency may be conveniently called N_a . It is used to modulate an oscillator 2. This oscillator is designed to generate any desired fixed super-audible frequency. An intermediate frequency, N_i , has here 30 been selected by way of illustration. Since this frequency is fixed the oscillator may be made more simple and more efficient than if it were variable. A tuning control is of course 35 eliminated. The result is a carrier wave of intermediate frequency N_i modulated by currents of audio frequencies N_a . These oscillations are passed through an intermediate frequency amplifier 3. This amplifier has always a limited 40 fixed frequency range $N_i \pm N_a$ to deal with. It may therefore be sharply responsive to these frequencies if desired, or, on the other hand, may be wholly untuned. In either case such an amplifier is simple and efficient, and does not require 45 a tuning control. It has thus all of the well recognized advantages of a fixed intermediate frequency amplifier. Following this amplifier is a detector 4 which converts the now amplified currents to audio frequencies N_a . 50 This detector may operate into any desired form of output circuit 5, as for example an audio frequency amplifier, telephones, or a loud speaker.

In Fig. 2 I have shown diagrammatically a 55 radio receiving set embodying my invention. Here I represents an input or receiving circuit, such for instance as an antenna or loop, and may also include any desired means for tuning the same to the frequency N_r of the incoming radio frequency signals. II is a radio frequency amplifier, and III is a detector giving currents of audio 60 frequencies N_a . It is followed by an audio frequency amplifier IV, the output of which is used to modulate the fixed frequency oscillator V. An intermediate frequency oscillator V, amplifier 65 VI and detector VII are illustrated as before. The resulting audio frequency currents may be fed directly to the desired output circuit, or may be again subjected to amplification. This may be carried out at the same frequency N_i , or at 70 another frequency N_i^1 , either higher or lower than the previous one. In Fig. 2 I have shown an audio frequency amplifier VIII used to modulate another intermediate frequency oscillator IX, generating a different intermediate frequency 75 N_i^1 . This is followed by another fixed interme-

diate frequency amplifier X designed to amplify frequencies $N_i^1 \pm N_a$. Detector XI, audio frequency amplifier XII, and output circuit XIII are arranged as before. It should be understood that in both this and the preceding figure the oscillator or oscillators may be designed to generate any super-audible frequency. They are only shown as generating a so-called intermediate frequency by way of example.

In Fig. 3 I have shown one form of circuit which I have found to be suitable for embodying my invention in a radio receiving set. The antenna-ground circuit A, G is coupled through transformer L_1 L_2 to input circuit I of radio frequency amplifier II. Any method of tuning may be employed, but I have here shown a variable condenser C_1 connected across the secondary L_2 of the transformer. The radio frequency amplifier II may be of the ordinary tuned regenerative type, or may be neutralized or balanced if desired. For instance, that type of radio frequency amplifier now commercially known as neutrodyne is suitable. The particular amplifier which I have shown in Fig. 3 is of the balanced radio frequency type invented by Stuart Ballantine and described and claimed by him in his copending application, Serial No. 629,702, filed April 3, 1923. In such an amplifier the impedance mesh is arranged as a Wheatstone's bridge in order to prevent reaction from the output circuit to the input circuit of the amplifier stage. I have shown a compensating condenser at C_2 and a balancing coil at L_3 , arranged for this purpose. This radio frequency amplifier is coupled through transformer L_4 L_5 to tuned circuit L_5 C_3 which is adjusted to the same frequency N_r as input circuit L_2 C_1 . This may conveniently be done by a single control as described and claimed in my copending application Serial No. 1,471, filed January 9, 1925. L_5 C_3 forms the input circuit for detector III having the usual grid condenser C_4 and leak resistance r_1 . A radio frequency by-pass condenser C_5 may be provided, as also a large by-pass condenser C_6 for the "B" battery B_1 . Detector III works through audio frequency transformer T_1 into any suitable audio frequency amplifier, here represented by IV. The audio frequency oscillations issuing from amplifier IV are now used to modulate oscillator V. A variety of different types of oscillator may be employed, as well as different methods of modulation. No particular form of oscillator or method of modulation is preferred, but I have here shown one which I have found to work satisfactorily. T_2 is an audio frequency transformer having a capacity C_8 shunted around its secondary to by-pass the oscillator frequency. L_6 and L_7 are oscillator coils which with condenser C_7 determine the frequency of oscillation. The various coils and condensers of the oscillator will ordinarily be designed to give whatever super-audible or intermediate frequency, N_i , may be preferred, and since this is conveniently pre-assigned and remains fixed, an oscillator adjustment is readily dispensed with. For simplicity in the diagram I have shown a separate "B" battery for the oscillator, at B_2 , by-passed by capacity C_9 . For the same reason, I have not shown either "A" batteries or "C" batteries in this diagram, since they are to be employed at the appropriate points in the conventional and well understood manner. While the method of modulation here shown is of the general plate-circuit type, I may use grid-circuit or any other convenient form of modulation.

The output from oscillator V is the fixed super-

audible or intermediate frequency Ni , modulated by audio frequency currents derived from the received signals. These oscillations are transmitted through transformer L_7 L_8 to fixed amplifier VI. The circuits L_8 C_{10} , and L_9 C_{11} are resonant to the chosen frequency Ni at which the oscillator and amplifier are designed to operate. This being fixed, a tuning control is unnecessary. The super-audible or intermediate frequency amplifier may be sharply responsive to the frequency Ni , but its resonance curve should, of course, be such as not to cut off the side-bands produced in the modulation of frequency Ni by currents of audio frequencies Na . It is, however, not essential to my invention that this amplifier should be sharply responsive, since the selectivity of the radio receiving set of which it is here shown as forming a part, does not depend upon the ability of the amplifier to reject undesired signals. I may therefore use a non-selective or wholly untuned amplifier at this point. Various forms of intermediate frequency amplifier may suitably be used. I have found, however, that the use of neutralized or partially balanced stages may be advisable in an intermediate frequency amplifier, for the suppression of self-oscillation therein. Furthermore, I find that it is sometimes desirable to advance still further, in balancing the stages of this amplifier, and I may therefore employ intermediate frequency amplifier circuits capable of complete balance at the intermediate frequency employed, thus isolating the output circuit of each stage from the input circuit of that stage and providing a substantially one-way repeater action in each of said stages. This one-way action in each stage tends to produce true cascade amplification in the intermediate frequency amplifier, as described and claimed in my copending application Serial No. 1,471, filed January 9, 1925. Accordingly in the embodiment of my invention shown in Fig. 3 I have shown in each stage of the intermediate frequency amplifier VI a balancing network of the Wheatstone bridge type, similar to the bridge network shown in the high-frequency amplifier II, and including compensating capacities C_{12} and C_{13} and balancing coils L_{10} and L_{12} . The plate coil L_{11} of the first intermediate frequency stage forms the primary of the transformer through which it is coupled to the second stage. The plate coil L_{13} of the second intermediate frequency stage forms the primary of transformer L_{13} L_{14} the secondary of which forms part of the detector input circuit L_{14} C_{14} . This circuit is fixed and resonant to the same range of frequencies as are circuits L_8 C_{10} and L_9 C_{11} , namely, $Ni \pm Na$.

Any form of detector or demodulator, whether of the crystal, vacuum bulb, or other type, may be used with my invention. At III and VII, I have illustrated a detector of the conventional audion type, that at VII being provided with the usual grid condenser C_{15} , grid leak r_2 , and by-pass condenser C_{16} . A separate "B" battery B_3 and large by-pass condenser C_{17} are here shown for simplicity. Audio frequency transformer T_3 conveys the detected currents to audio frequency amplifier VIII, which is here shown as having two stages coupled by audio frequency transformer T_4 . The last stage may work into any desired utilization circuit, such as telephones, or a loud speaker, represented at XIII.

A circuit like that above described has been found to work well in practice. It is of course capable of many variations. The number of amplifier stages may obviously be increased or di-

minished. Another oscillator and super-audible or intermediate frequency amplifier, working on the same or different frequency, may obviously be inserted after detector VII or after audio frequency amplifier VIII. This would be followed by another detector and audio frequency amplifier as shown in Fig. 2. Two or more stages of radio frequency amplification like that shown at II, or of any other suitable kind, may be employed. Various kinds of audio frequency amplification as for instance that known as "push-pull" amplification, are suitable. Obviously as many stages of intermediate frequency amplification as are desired may be used at VI. My invention is not confined in any way to intermediate frequency amplification, and I employ any super-audible frequency which I find convenient, whether this frequency is in the ranges commonly spoken of as intermediate frequencies, or radio frequencies, or both, or is above or below either of these ranges. The audio frequency amplifier at IV may be omitted if desired, allowing the audio frequency currents from detector III to modulate oscillator V, or more audio frequency amplifier stages may be inserted at IV.

In order to illustrate some of the above mentioned variations, I have shown a more simple form of radio receiving circuit embodying my invention, in Fig. 4. In this case I have shown individual "A" batteries, "B" batteries and "C" batteries in each stage in order to still further simplify the diagram. The "B" batteries are suitably by-passed by condensers C_8 . The input circuit I is followed by a radio frequency amplifier II having two tuned regenerative stages. A tickler coil is shown at L_{15} although sufficient regeneration may often be obtained without its use. Radio frequency amplifier II works into detector III which is used to modulate oscillator V by means of transformer T_1 . A method of grid-circuit modulation is here shown. The modulated oscillations are amplified by fixed amplifier VI. No neutralization or balancing is used in this amplifier. It is coupled through transformer L_{13} L_{14} to the second detector VII which works into a single audio amplifier stage VIII and reproducer XIII.

The circuit of Fig. 4 is merely typical of numerous other circuits which are suitable to my invention. Reflexing systems may of course be used. One such system would be to use the last intermediate frequency amplifier stage as an audio frequency amplifier as well. Any of the well-known forms of oscillator, or systems of modulation, may of course be used at V. My invention may, moreover, be advantageously embodied in circuits which are used for short-wave radio receivers, and is of peculiar advantage in such a case because of the difficulties commonly met with in a short-wave amplifier. Intermediate frequency amplification, especially according to the system herein described, affords a desirable method of avoiding these difficulties.

The word reflexing is commonly employed to designate the use of the same audion tube as both a high frequency and a low frequency amplifier. I have explained above how this may be done. An analogous scheme is to use the same audion tube as both an audio frequency amplifier and an oscillator. A suitable circuit is that shown in Fig. 5, only the relevant portions being included. Radio frequencies in tuned circuits L_5 C_3 are detected by detector III and the resulting audio frequency currents are first amplified by the tube shown at IV and V, and then used

to modulate the super-audible frequency oscillations produced by the same tube. L_{16} is a choke coil having high audio frequency impedance. The coupling between the oscillator and the succeeding intermediate frequency amplifier should be loose in order to prevent paralysis of the amplifier. C_8 is a by-pass condenser having a high impedance to frequencies N_d but a low or negligible impedance to the oscillator frequency N_i .

10 In practice I have found that some systems employing my invention for operating a loud speaking telephone may be subject to acoustical feedback from the telephone into the oscillator circuit. The extent of this phenomenon, which 15 may produce sustained audio frequency oscillations, is determined largely by the amplitude of the carrier-frequency oscillations N_i , which are continuously fed into the fixed amplifier. Therefore in any physical structure, the coupling between the oscillator and its succeeding amplifier should preferably be carefully adjusted, such adjustment depending to some extent upon how 20 much amplification is employed prior to modulation of the oscillator. When this coupling is 25 once fixed for a given structure it need not be thereafter altered.

Numerous variations and modifications other than those herein especially pointed out will be seen to fall within my invention.

30 I claim:

1. An electrical circuit for amplifying audio frequency currents at intermediate frequencies comprising, in combination, a source of audio frequency currents to be amplified; a local source 35 of currents having a fixed intermediate frequency; means whereby said audio frequency currents are caused to modulate said local intermediate frequency currents; a balanced and substantially unidirectional amplifier for said modulated intermediate frequency currents; a detector for said amplified intermediate frequency currents; a second local source of currents having a different fixed intermediate frequency; means whereby said detected currents are caused to 40 modulate said second local source of intermediate frequency currents; a second balanced and substantially unidirectional amplifier for said second modulated intermediate frequency currents; and a second detector for said last mentioned 45 amplified intermediate frequency currents.

2. A radio receiving circuit comprising, in combination, a device for receiving incoming radio frequency signals; a radio frequency amplifier for said incoming signals comprising a vacuum 55 tube and an impedance mesh associated therewith and arranged in the form of an alternating current Wheatstone's bridge of which the input and output circuits of the amplifier stage form conjugate arms, whereby reaction from the output circuit to the input circuit is reduced or substantially prevented; a detector for said amplified 60

radio frequency currents; a local source of currents having a fixed intermediate frequency; means whereby said detected radio frequency currents are caused to modulate said local intermediate frequency currents; a balanced and substantially unidirectional amplifier for said modulated intermediate frequency currents; a detector for said amplified intermediate frequency currents; and a responsive device actuated by the resulting detected currents.
